UNITED STATES PATENT OFFICE.

CHARLES L. FETTERLY, OF PHILADELPHIA, PENNSYLVANIA, ASSIGNOR TO KIL-MARNOCK TEXTILE MANUFACTURING CO., OF PHILADELPHIA, PENNSYLVANIA, A CORPORATION OF ILLINOIS.

DESIGN FOR A RUG.

40,470.

Specification for Design.

Patented Jan. 25, 1910.

Application filed November 15, 1909. Serial No. 528,265. Term of patent 3½ years.

To all whom it may concern:

Be it known that I, CHARLES L. FETTERLY, a citizen of the United States, residing in Philadelphia, Pennsylvania, have invented a certain new, original, and ornamental Design for Rugs, of which the following is a specification, reference being had to the accompanying drawing, the view of which is a section of the rug.

I claim:

The ornamental design for a rug, as shown.

CHARLES L. FETTERLY.
